NISON Tregor

BY

Thomas J. Donnelly

ATTORNEY.

UNITED STATES PATENT OFFICE

NISON TREGOR, OF DETROIT, MICHIGAN

DESIGN FOR A TOY SAVINGS BANK

Application filed November 26, 1928. Serial No. 29,030. Term of patent 14 years.

To all whom it may concern:

Be it known that I, NISON TREGOR, a citizen of the Union of Socialist Soviet Republics of Russia, and residing at Detroit, in the county of Wayne and State of Michigan, have invented a new, original, and ornamental Design for a Toy Savings Bank, of which the following is a specification, reference being had to the accompanying drawing, forming a part hereof and in which—

Fig. 1 is a front elevational view of a toy savings bank showing my new design.

Fig. 2 is a side elevation of the same.

I claim:

The ornamental design for a toy savings bank as shown.
